United States Patent Office.

CHARLES DAHLINGER, OF ALLEGHENY, PENNSYLVANIA.

Design No. 3,913, dated March 22, 1870.

DESIGN FOR BURIAL CASKETS.

The Schedule referred to in these Letters Patent and making part of the same.

To all whom it may concern:

Be it known that I, CHARLES DAHLINGER, of the city of Allegheny, in the county of Allegheny and State of Pennsylvania, have produced a new Design for Burial-Caskets and Coffins; and I do hereby declare the following to be a full, clear, and exact description thereof, reference being had to the accompanying drawing making a part hereof, in which—

Figure 1 is a perspective view of a burial casket, illustrative of my improved design.

Figure 2 is an end view thereof, and

Figure 3 is a section of fig. 2 through the line $x-x$.

Like letters of reference indicate like parts.

My improved design for burial-caskets and coffins is confined to the conformation of the head-piece and foot-piece of the casket or coffin, and consists in making these parts each of five sides of equal or nearly equal length or width, and each placed at an angle to the other, the contained angles being equal or nearly so, and this irrespective of the exterior surface of the pieces composing the top and bottom, which may be plane, ogee, or otherwise curved or ornamented.

Thus, in fig. 1, a a' a'' represent three of the five sides, the remaining two corresponding in form to those shown at a' a . The side a' is shown with a panel.

In figs. 2 and 3 the side b'' is shown paneled, and the remaining four sides, b b' , each with an ogee face,

but, in any case, other forms of curvature or ornamentation may be adopted for the face.

The mode of applying the ogee ornamentation to the plan pentagonal sides is illustrated in fig. 3, where the lines s s indicate the pentagonal form which I claim.

In the construction of coffins and burial-caskets a swell is made at or near the "chest," so called, and the sides taper either in curved or straight lines from that point, either way, to or toward the ends. It will be observed that in the design described the pentagonal ends are exclusive of and are included between the extremities of such tapering sides.

What I claim as my improved design for coffins and burial-caskets, and desire to secure by Letters Patent, is—

The pentagonal form for the ends, the faces constituting such pentagonal form being exclusive of and included between the extremities of the tapering sides, as described and shown.

In testimony whereof I, the said CHARLES DAHLINGER, have hereunto set my hand.

CHARLES DAHLINGER.
